United States Patent Office

Des. 180,781
Patented Aug. 13, 1957

180,781

SETTEE OR SIMILAR ARTICLE

Bertis F. Hamilton, Earl F. Hamilton, and William S. Hamilton, Columbus, Ind.; said William S. Hamilton, executor of said Bertis F. Hamilton, deceased, assignors to Hamilton Manufacturing Corporation, Columbus, Ind., a corporation of Indiana

Application May 31, 1955, Serial No. 36,288

Term of patent 14 years

(Cl. D15—11)

Fig. 1 is a perspective view of a settee or similar article, showing our new design;

Fig. 2 is a rear elevation of the same; and

Fig. 3 is a side elevation thereof.

The dotted lines in Figs. 1 and 2 indicate indeterminate length.

We claim:

The ornamental design for a settee or similar article, as shown and described.
